(No Model.)

H. MILLER.
Soldering Apparatus.

No. 243,287.

Patented June 21, 1881.

UNITED STATES PATENT OFFICE.

HERMAN MILLER, OF NEW YORK, N. Y.

SOLDERING APPARATUS.

SPECIFICATION forming part of Letters Patent No. 243,287, dated June 21, 1881.

Application filed March 5, 1881. (No model.)

To all whom it may concern:

Be it known that I, HERMAN MILLER, of the city and county of New York, in the State of New York, have invented certain new and useful Improvements in Soldering Apparatus, of which the following is a specification.

My invention relates to apparatus for soldering the corner seams of sheet-metal cans, especially square cans, in which the can to be 10 soldered is moved past and has its seam which is to be soldered immersed or passed through a stationary solder-vessel, or first in an acid or flux vessel and then in a solder-vessel, and subsequently, if desirable, in a water-vessel, 15 for cooling.

In the machine or apparatus for which were granted to me Letters Patent No. 190,888, dated May 15, 1877, the cans are inserted in holders which travel in a circular path past 20 several series of acid, solder, and water vessels, equal in number to the number of sides which the cans have, and through which the corners of the cans are passed, and the rising-and-falling movement necessary to immerse the 25 cans in the vessels, and to raise them in passing from one vessel to another, is imparted to the can-holders by a sinuous track, upon which said holders bear. In my present invention, which constitutes a more simple apparatus, 30 and yet admits of the employment of unskilled labor, the cans are not inserted in holders, but are supported upon a stationary rail or track, which extends through or over the vessels, and which comprises raised portions at the points 35 where the cans are transferred from one vessel to another; and upon this rail or track the cans are so supported that their corners may be immersed to the proper depth while they are moved over the said track, either by hand 40 or by simple mechanical devices, such as endless belts with attached pushers.

The invention consists in the combination, with a solder-vessel, of a track or rail upon which the corner of a can may rest and be 45 moved along, and which is arranged below the surface-line of the solder, and comprises raised portions at the ends of the vessel for lowering the cans into and raising them out of the vessel.

It also consists in the combination, with the 50 solder-vessel and a track or rail for supporting the can with one of its corners immersed in the solder, of guide-rails upon each side of

said supporting track or rail, along which the cans are to be moved, and one of which may be provided with a projecting stop, against 55 which the lower edge or corner of the can strikes and is held while the can is turned over to present a new seam for soldering. The cans, as hereinbefore mentioned, might be moved past and through the several vessels by hand; 60 but I prefer to move them by machinery.

The invention also consists in the combination, with a series of vessels and a track or rail arranged below the surface-line of the contents of said vessels, upon which the cans are 65 supported and moved along, and which comprises elevated portions between the vessels, of an endless belt or band, to which are attached pushers, which act upon the cans and move them forward past the several vessels 70 and along the said track or rail.

The invention also consists in novel details of construction and combinations of parts, to be hereinafter described.

In the accompanying drawings, Figure 1 represents a side view of a portion of an apparatus embodying my invention. Fig. 2 is a plan of the several vessels, with the rail over which the cans are moved and the side guide-rails; and Fig. 3 represents a transverse vertical section upon the dotted line *x x*, Fig. 1.

Similar letters of reference designate corresponding parts in all the figures.

A designates the cans to be soldered, and B, C, and D designate, respectively, an acid 85 or flux vessel, a solder-vessel, and a water or cooling vessel, which I will first describe. These three vessels form a series adapted for soldering a single seam, and if the four bottom or top seams of a rectangular can are to 90 be soldered, there should be four series of vessels. The solder-vessel C has beneath it a fire-place, which is supplied with air by a blast-pipe, E, to which it is connected by branch pipes *a*, and from the fire-place the smoke and 95 heated products of combustion pass through a flue, *b*, into a chamber, B', below the acid-vessel, which is adjacent to the solder-vessel, and thence out the smoke-pipe F. By this means the acid or flux vessel is heated, and the cans 100 which pass through it before entering the solder-vessel are warmed sufficiently to prevent them from chilling the melted solder. The water-vessel D is supplied by a suitably-ar-

ranged pipe with cold water, and after passing through a solder-vessel the cans pass through a water-vessel before they are turned and enter the next acid-vessel. Between each solder-vessel C and its succeeding cooling-vessel may be arranged a stationary scraper, e, over which the cans pass, and by which the superfluous solder is removed.

G designates a continuous track or rail, which is represented as arranged centrally along the several vessels. The portions of this track or rail which nearly correspond in length to the lengths of the vessels are arranged below the surface-line of acid, solder, or water therein, and so much below the surface that a can supported by it would have its corner seam that it is desired to solder immersed or dipped to the proper depth. Between the several vessels are raised portions G' of the track or rail G, which bridge over the space from one vessel to another, and serve to raise the cans out of one vessel and then to lower them into the next vessel. In order to steady the cans in their movements, I provide guide-rails H, one on each side of the track or rail G, and between them the can A fits loosely, as seen in Fig. 3, and is prevented from too great side movement as it is moved along the rail or track G. The guide-rails H do not confine the cans at all, but simply steady them as they are moved along, and enable the cans to be so moved by simply pushing them along.

Between the acid-vessel B and the adjacent solder-vessel C, opposite an elevated part of the track or rail, is a brush or brushes, d, arranged adjacent to the track or rail G, and after being immersed in or passed through the acid or flux the can is moved past said brush or brushes, and the surplus acid is removed therefrom. The can A, being placed between the guide-rails H, with its corner-seam which is to be soldered resting upon the track or rail G, is pushed along by hand or by pushers, hereinafter described, first through the acid-vessel B and past the brush or brushes d, then over the raised portion G' of the track or rail G between the acid-vessel and solder-vessel, whereby it is transferred from the former to the latter, thence through the solder-vessel and over the raised portion G' between the solder-vessel and cooling-vessel D, whereby it is transferred to and through the cooling-vessel D. After passing from the cooling-vessel the lower front edge, which rests upon one of the guide-rails H, strikes a stop, e, upon the said rail, and is thereby stopped, while pushing on the can tends to roll the can over, so as to bring a second seam to rest upon the rail or track G, whereupon the operation is repeated with said second seam and successively with all four seams until all are soldered.

The guide-rails H may have elevated portions H' in them corresponding with the portion G' of the track or rail G; but this is not necessary, as they might be straight.

The cans might be pushed along the track or rail G by hand; but I prefer to do it by ma-

chinery, and have here represented an endless belt, K, mounted on pulleys L, and having attached to it arms M, which form pushers for pushing the cans along. Each series of three vessels should have a separate belt, K, in order to provide for more readily turning the cans when they strike the stop e, without binding or cramping them, and the pulleys L and L', which carry the adjacent sections, may be mounted upon a single shaft, as seen in Fig. 3, side by side.

The apparatus might be employed for soldering the corner side seams as well as the bottom seams.

What I claim as my invention, and desire to secure by Letters Patent, is—

1. The combination, with a solder-vessel, of a stationary track or rail, upon which the corner of the can may bear and be moved along, and which is arranged below the surface-line of the solder, and comprises elevated portions at the ends of the vessel, whereby the can is lowered into and raised out of the vessel, substantially as specified.

2. The combination, with a solder-vessel, of a track or rail upon which the edge of the can may bear and be moved along, which is arranged below the surface-line of the solder, and comprises elevated portions at the ends of the vessel, and guide-rails arranged one upon each side of and above said track or rail, substantially as and for the purpose specified.

3. The combination, with series of vessels, of a track or rail upon which the cans may be supported and be moved along, and which is arranged below the surface-line of the acid and solder, and comprises elevated portions between the vessels for transferring the cans from one vessel to another, and guide-rails, one upon each side of and above said track or rail, substantially as specified.

4. The combination, with series of vessels, of a track or rail upon which the cans may be supported and be moved along, and which comprises elevated portions between the vessels, and stationary stops arranged in the path of the cans for turning the cans, substantially as specified.

5. The combination, in a soldering apparatus, with series of acid and solder vessels, of a can-supporting track or rail comprising elevated portions between the vessels, and an endless belt traveling in line with said track or rail, and carrying pushers for moving the cans along, substantially as specified.

6. The combination, in a soldering apparatus, with several series of vessels, of a continuous track or rail elevated between the vessels, stationary stops arranged in the path of the cans, and endless belts, one for each series of vessels, carrying pushers for moving the cans, substantially as specified.

HERMAN MILLER.
